[57] CLAIM

The ornamental design for a safety syringe bulb, as shown and described.

DESCRIPTION

FIG. 1 is a perspective view of a safety syringe bulb showing my new design;

FIG. 2 is a front elevational view thereof;

FIG. 3 is a rear elevational view thereof;

FIG. 4 is a left side elevational view thereof, the right side elevational view being a mirror image thereto;

FIG. 5 is a top plan view thereof; and,

FIG. 6 is a bottom plan view thereof.

The broken line showing in FIGS. 1 through 6 of the portions of the syringe bulb are for illustrative purposes only and forms no part of the claimed design.
